Primary Examiner — Deanna L Pratt*(45) Attorney, Agent, or Firm* — Cantor Colburn LLP(57) **CLAIM**

The ornamental design for a display screen or portion thereof with animated graphical user interface, as shown and described.

DESCRIPTION

FIG. 1 is the first image in a sequence for an animated sequence for a display screen or portion thereof with animated graphical user interface showing our new design, FIG. 2 is the second image thereof; FIG. 3 is the third image thereof; FIG. 4 is the fourth image thereof; FIG. 5 is the fifth image thereof; FIG. 6 is the sixth image thereof; FIG. 7 is the seventh image thereof; FIG. 8 is the eighth image thereof; and, FIG. 9 is the ninth image thereof.

The appearance of the animated user interface sequentially transitions between the images shown in FIGS. 1-9. The process or period in which one image transitions to another forms no part of the claimed design. The broken lines showing of a display screen or portion thereof with graphical user interface are for environmental purposes only and form no part of the claimed design.
